UNITED STATES PATENT OFFICE.

TOBIAS MILLER, OF CLEVELAND, OHIO.

AUXILIARY SEAT.

1,302,828.

Specification of Letters Patent.

Patented May 6, 1919.

Application filed August 12, 1918. Serial No. 249,550.

To all whom it may concern:

Be it known that I, TOBIAS MILLER, a citizen of the United States, residing at Cleveland, Ohio, have invented a new and useful 5 **Auxiliary Seat**, of which the following is a specification.

This invention relates to a new and useful improvement in auxiliary seats of a type especially useful in connection with automobiles and other vehicles, although it may 10 be applied elsewhere if desired.

The object of the invention is to provide an improved chair or seat which can be folded and stored in small space when not in 15 use, but which when erected, has four legs, which make it strong and dependable as an ordinary chair.

The chair is so constructed that the two front legs and the two rear legs are rigid 20 with each other, and when the chair is collapsed, these legs fold under the seat. A pack is provided which folds down upon the seat. When the chair is erected, the legs are locked in upright position.

25 In the accompanying drawings,

Figure 1 is a side elevation of the chair erected.

Fig. 2 is a similar view of the same folded.

Fig. 3 is a detail of one of the leg joints.

30 Fig. 4 is a detail showing the connection of the legs with the floor.

Referring specifically to the drawings, 1 indicates the seat, which sets between two hollow side frames or casings 2, to each of 35 which the front leg 3 is pivoted by a bolt 4 to ears 5 depending from the frames. Near its upper end, the leg has a hole 6 to receive a locking pin 7 supported in a recess in the frame 2, the pin being pressed behind by a 40 spring 8, confined by a screw plug 9. The leg has a lip 10, which stops against the frame 2, when the leg is in vertical position.

The rear leg unit 11, is pivoted at 12, to the under side of the seat frame, near the 45 rear thereof, and swings forwardly under the seat, as indicated by the dotted line 13, the legs 11 being set close enough together to swing between the front legs.

The rear leg unit has an extension 14 at 50 its upper end, provided with a slot 15, this extension swinging within a cavity in the seat frame. A locking rod 16, at each side, is connected to the extension 14 by a pin 17, which works in the slot 15, and this rod 16 55 is also attached by a pin 18, to an ear 19 on

a locking plug 20. The pin 17 also connects the rod 16 to an arm 23 depending from the folding back 21, which is pivoted at 22 to the seat frame.

The front legs 3 are connected at their 60 lower ends by a cross bar which is pivoted at 24, at the middle line of the seat, to a foot frame 25, the toes of which extend through slots in runways 26 which are set in the floor, and the toes are provided with 65 rollers 29, which travel back and forth in the runways or tracks. The foot piece also has a heel 28, adapted to engage in a hole in the track member 26, as shown in Fig. 1, when the chair is pulled out and set up.

In operation, by folding down the back 70 21, the rods 16 are pulled rearwardly, withdrawing the plugs 20 from their locking position above the front legs 3. The rear legs can then be folded under the seat, and 75 then the front legs similarly folded under the seat, as shown in Fig. 2, the pin 17 traveling in the slot 15, when the parts are folded, and the feet 25 swinging on the rollers 29 and through the slot in the track 80 casing 26. Then the whole chair may be pushed along the tracks to stored position as under an automobile seat or the like. When the chair is to be erected, it is first pulled out, and then swung up on the front legs. 85 The back is then swung up and the same action causes the rear legs to swing down to a vertical position, and by means of the rods 16, the locking plugs 20 are advanced to position above the front legs and lock said legs 90 in erect position. The chair as a whole may be turned on the pivot 24 to face it in different directions if desired.

I claim:

1. A folding chair comprising a seat, front 95 and rear legs pivoted to said seat to fold up under the same, and locking devices connected to the rear legs and slidably to locking engagement with the front legs, when the legs are unfolded.

2. A folding chair comprising a seat frame, front and rear legs pivoted to the seat frame to fold up under the same, a back pivoted to the seat frame to fold down upon the same, and operative connections between the back and the rear legs, adapted to unfold the latter when the back is unfolded.

3. The combination with floor tracks, of a foot piece, having rollers engaged in said tracks, a chair having front legs connected 110

by a cross bar, and a vertical pivot connecting the foot piece and the cross bar, whereby the chair may be faced different ways and shifted to different positions.

5. 4. A folding chair comprising a seat frame, front and rear legs pivoted to said frame to swing up under the same, a folding back hinged to the seat frame, said back and rear legs having lever extensions projecting into the seat frame, a rod pivotally connected at its rear end to said extensions, and adapted to slide back and forth in the seat frame, and a locking member carried at the front end of said rod and adapted to engage between the seat frame and the top

of the front legs when the latter are unfolded.

5. The combination with floor tracks, of a chair having folding legs, and a foot piece connected to said legs and pivotally engaging the tracks and slideable along the same, the foot piece having heel plugs engageable with the tracks when the legs are unfolded, to latch the foot piece to the tracks. 20

TOBIAS MILLER.
